US00D921486S

(12) **United States Design Patent** (10) Patent No.: **US D921,486 S**
(45) Date of Patent: ** Jun. 8, 2021

(54) **SPRAY HEAD**

(71) Applicant: **The Procter & Gamble Company**,
Cincinnati, OH (US)

(72) Inventors: **Pieter Dirk Jenny Maria Van Den Bergh**, St. Martens Latem (BE);
Richard Hagee, Cincinnati, OH (US);
Mark Armstrong, London (GB)

(73) Assignee: **The Procter & Gamble Company**,
Cincinnati, OH (US)

(**) Term: **15 Years**

(21) Appl. No.: **29/695,721**

(22) Filed: **Jun. 21, 2019**

(30) **Foreign Application Priority Data**

Dec. 21, 2018 (WO) 970003723

(51) LOC (13) Cl. **09-07**

(52) U.S. Cl.

(57) **CLAIM**

The ornamental design for a spray head, as shown and described.

DESCRIPTION

FIG. 1 is a perspective view of a spray head;
FIG. 2 is a front view of the spray head shown in FIG. 1;
FIG. 3 is a back view of the spray head shown in FIG. 1;
FIG. 4 is a right side view of the spray head shown in FIG. 1;

FIG. 5 is a left side view of the spray head shown in FIG. 1;

FIG. 6 is a top view of the spray head shown in FIG. 1; and,
FIG. 7 is a bottom view of the spray head shown in FIG. 1.
The broken lines depict portions of the spray head that form
no part of the claimed design.

1 Claim, 7 Drawing Sheets
